[57] CLAIM

The ornamental design for a power and utility distribution pedestal for boats and recreational vehicles, as shown and described.

DESCRIPTION

FIG. 1 is a front and one side perspective view of the power and utility distribution pedestal for boats and recreational vehicles showing my new design;

FIG. 2 is an opposite side elevational view thereof;

FIG. 3 is a rear elevational view thereof;

FIG. 4 is a top plan view thereof, the bottom being plain and unornamented.

FIG. 1

FIG. 2

FIG. 3

FIG. 4
